United States Patent

Des. 235,752
Patented July 8, 1975

235,752

LIFT TRUCK BODY

Darrell C. Fuller and William A. Williamson, Niles,
Mich., assignors to Clark Equipment Company

Filed Apr. 23, 1973, Ser. No. 353,862

Term of patent 14 years

Int. Cl. D12—05

U.S. Cl. D12—61

FIG. 1

FIG. 3

FIG. 2

FIG. 4

FIG. 5

FIG. 6

FIG. 1 is a right side elevational view of a lift truck body showing our new design;

FIG. 2 is a right front perspective view;

FIG. 3 is a front elevational view;

FIG. 4 is a top rear perspective view;

FIG. 5 is a right rear perspective view; and

FIG. 6 is a rear perspective view thereof.

The left side of the lift truck body is a mirror image of the right side shown herein.

The portions shown in broken lines in the drawing are for illustrative purposes only.

We claim:

The ornamental design of a lift truck body, as shown and described.
